UNITED STATES PATENT OFFICE.

GEORGE R. BLAKE, OF WINCHESTER, VIRGINIA.

DESIGN FOR A LEMON-SQUEEZER.

SPECIFICATION forming part of Design No. 27,948, dated December 7, 1897.

Application filed August 6, 1897. Serial No. 647,385. Term of patent 7 years.

To all whom it may concern:

Be it known that I, GEORGE R. BLAKE, of Winchester, in the county of Frederick and State of Virginia, have invented and produced a new and original Design for a Lemon-Squeezer, of which the following is a specification, reference being had to the accompanying drawings, forming a part thereof, in which—

10 Figure 1 is a perspective view of a lemon-squeezer embodying the features of my design. Fig. 2 is a vertical section of the squeezer, and Fig. 3 is a bottom plan view of the squeezer.

15 My design relates particularly to that class of lemon-squeezers adapted to rest upon a glass or other receptacle.

The leading features of the design reside in a base A, whose upper surface a is con-

caved and whose under surface a' is provided 20 with circular corrugations a² and a plain center a⁴, and the design particularly resides in the cone C, supported at an elevation from the base and connected with its upper central portion by a column B of less diameter 25 than the diameter of the base of the cone.

A further feature of the design consists in segmental openings a⁵, centrally grouped around the central portion of the base and appearing in the corrugated bottom at its de- 30 pressions a³.

I claim—

The design for a lemon-squeezer herein shown and described.

GEORGE R. BLAKE.
